UNITED STATES PATENT OFFICE.

EMERSON E. HOLTZ, OF BILLINGS, MONTANA, ASSIGNOR OF ONE-FOURTH TO HUGH B. STRIDIROK AND ONE-FOURTH TO ELMER KOWALK, BOTH OF BILLINGS, MONTANA.

METAL FLUME OR TROUGH.

1,022,138.

Specification of Letter's Patent.

Patented Apr. 2, 1912.

Application filed July 3, 1911. Serial No. 636,582.

To all whom it may concern:

Be it known that I, EMERSON E. HOLTZ, a citizen of the United States, residing at Billings, county of Yellowstone, State of Montana, have invented certain new and useful Improvements in Metal Flumes or Troughs, of which the following is a specification, reference being had therein to the accompanying drawing.

10 This invention relates to certain new and useful improvements in metal flumes or troughs, the object being to provide a flume which is formed of a plurality of sections having interlocking expansible joints at 15 their ends whereby the complete flume will be allowed to contract and expand, thereby overcoming the difficulties existing in flumes now in use.

Another object of the invention is to provide a novel form of hanger whereby the sections will be supported in a rigid manner at their interlocking ends so as to prevent any danger of sagging or crimping of the flume by excessive weight.

25 A further object of the invention is to provide novel means for clamping the interlocking sections together whereby an exceedingly tight joint can be formed.

A still further object of the invention is 30 to provide novel means for operating the clamping member whereby the same will be forced firmly into position.

Other and further objects of the invention will be hereinafter set forth and the 35 novel features thereof defined by the appended claims.

In the drawing—Figure 1 is a transverse section through my improved flume or trough; Fig. 2 is a longitudinal section 40 through the same showing the interlocking connection at the overlapping ends; Fig. 3 is a detail vertical section of a modified form of wedging member for forcing the clamping member into position; and Fig. 4 is a detail view of another form of wedging member.

Like numerals of reference refer to like parts in the several figures of the drawing.

In the drawing, 1, 2 and 3 indicate semi-50 cylindrical sections of sheet metal having their adjacent ends overlapped as clearly shown in Fig. 2 forming a continuous conduit capable of being employed for various purposes. One end of each section is provided with spaced transverse semi-circular

beads 4 forming a central portion 5 adapted to receive the end portion 6 of the adjacent section, said section being provided with a similarly constructed bead 7 adapted to interlock or straddle the adjacent bead 60 4 in such a manner, that a slight space is formed between the respective interlocking beads in order to allow for contraction and expansion of the sections. The interlocking beads may fit snugly one within the 65 other and the same expansion of the sections be maintained as it will be seen that each bead of the respective sections has a free movement.

The flume may be supported by any suitable means but is herein shown arranged upon supports 8 which comprise a base 9 having standards 10 on the upper ends of which are arranged longitudinal angle irons 11 over which are arranged the angled ends 75 12 of substantially semi-circular hangers 13 which conform to the configuration of the sections. The hangers 13 are preferably formed of wide bands, as shown, of such width that a support is formed for the overlapping ends of the respective sections and the beads formed thereon.

The overlapping ends 5 and 6 of the sections are clamped together by a clamping member 14 which is substantially semi-circular in shape and comprises a band of such width that it will fit snugly between the beads of the respective sections, the upper ends being normally in a plane slightly above the angled ends 12 of the 90 hangers 13. The clamping member 14 is forced down into position by wedging members 15 and as shown in Fig. 1, the wedging members are carried by a transverse bar 16, the free end of which extends 95 over the angled ends 12 of the hangers 13, and are provided with openings to receive bolts 17 which pass up through the angle irons 11 and angled ends 12 and are provided with nuts 18 for forcing the bar 100 downwardly thereby forcing the clamping member into position.

In Fig. 4, a slightly modified form of clamping member is shown which comprises a T-bar 19, the ends of which are flattened 105 and shaped to form wedging members 20 adapted to engage the clamping member 14 in a similar manner to the wedging members 15.

In the modification shown in Fig. 3, a 110

wooden support 21 is shown over which is arranged the angled end 22 of a hanger 23 which is bolted in position as shown at 24 and carries a vertical clamping bolt 25 on 5 which is mounted a wedging member 26 having a wedging portion 27 adapted to be forced into engagement with the clamping member 14 by tightening the nut 28 carried by the bolt 25 which will securely lock the 10 overlapping portions of the flume sections in a similar manner to the wedging member previously described. In this construction, it will be seen that the hangers are secured to the wood support and the wedging members 15 so arranged and mounted that they will force the clamping member in such a manner that all danger of the same moving in any way is prevented and at the same time a flume is formed with an unobstructed 20 passage.

Having described my invention and set forth its merits what I claim and desire to secure by Letters Patent is—

1. A flume having overlapping ends provided with interlocking expandible beads, and means for clamping the overlapping ends of one side of the interlocking beads.

2. A flume comprising semi-cylindrical sections, one end of each section being provided with spaced semi-circular beads, the other end of said section having a single semi-circular bead adjacent its end.

3. In a device of the kind described, the combination with two sections having interlocking ends, of a hanger arranged under said interlocking ends, a clamping member for engaging said sections to one side of the interlocking ends and holding said sections in interlocked position, and wedging members for forcing said clamping member into position.

4. In a device of the kind described, the combination with two sections having overlapping ends and provided with interlocking beads, of a hanger arranged under said ends, a clamping member for engaging the inner section to one side of its interlocked connection, and a wedging member for forcing and holding said clamping member in 50 position.

5. In a device of the kind described, the combination with two sections having over-

lapping interlocking ends, of a support, a hanger carried on said support conforming to the configuration of said sections, a 55 clamping member arranged against the inner face of the inner section to one side of the interlocked connection, and wedging members for forcing said clamping member in position.

6. A flume or trough formed of a plurality of semi-cylindrical sections having overlapping ends, one end of each section being provided with spaced transverse semi-circular beads, the other end of said section having a semi-circular transverse bead adapted 65 to straddle the end bead of the adjacent section, and clamping means for holding said sections together.

7. In a device of the kind described, the combination with semi-cylindrical sections having overlapping and interlocking beads at their ends, of a hanger arranged under said sections at their overlapping portions, a support for said hanger, a clamping member engaging the inner face of the inner section, wedging members adapted to engage the free end of said clamping member, and means for operating said wedging members.

8. A flume or trough formed of a plurality of sections, each section having spaced transverse beads at one end and a single bead adjacent its other end, the free end of one section being adapted to engage the portion between the beads of the adjacent section, and a clamping member for holding said sections in engagement with each other.

9. A flume or trough composed of a plurality of semi-cylindrical sections having overlapping ends, the end of one section being provided with spaced transverse semi-circular beads, the opposite end of said section being provided with a bead adjacent its end adapted to straddle the bead at the 90 free end of the adjacent section, and means for clamping the free end of one section between the beads of the adjacent section.

In testimony whereof I affix my signature in presence of two witnesses.

EMERSON E. HOLTZ.
